(57) CLAIM

The ornamental design for a tubing clamp, as shown and described.

DESCRIPTION

FIG. 1 is a front isometric view of the tubing clamp illustrated in a closed position.

FIG. 2 is a rear isometric view of the tubing clamp illustrated in the closed position.

FIG. 3 is a front view of the tubing clamp illustrated in the closed position.

FIG. 4 is a rear view of the tubing clamp illustrated in the closed position.

FIG. 5 is a right side view of the tubing clamp illustrated in the closed position, with the left side view being a mirror image thereof.

FIG. 6 is a top view of the tubing clamp illustrated in the closed position.

FIG. 7 is a bottom view of the tubing clamp illustrated in the closed position.

FIG. 8 is a front isometric view of the tubing clamp illustrated in an open position.

FIG. 9 is a rear isometric view of the tubing clamp illustrated in the open position.

FIG. 10 is a front view of the tubing clamp illustrated in the open position.

FIG. 11 is a rear view of the tubing clamp illustrated in the open position.

FIG. 12 is a right side view of the tubing clamp illustrated in the open position, with the left side view being a mirror image thereof.

FIG. 13 is a top view of the tubing clamp illustrated in the open position; and,

FIG. 14 is a bottom view of the tubing clamp illustrated in the open position.

The dash-dot lines are for environmental purposes and form no part of the claimed invention.

1 Claim, 10 Drawing Sheets
